ELECTROMAGNETIC CONTROL DEVICE

Hans Münz, Kornthal, near Stuttgart, Germany;
vested in the Alien Property CustodianApplication May 12, 1939, Serial No. 273,332
In Germany May 27, 1938

2 Claims. (Cl. 171—229)

The invention relates to an electromagnetic control device for use with regulators or charging switches, in particular with combined regulators and switches, for electrical installations as used in vehicles, having a current winding, disposed in the magnetic circuit outside of the magnetic core.

According to the present invention an auxiliary magnet, having its own pole core on which the current coil is wound, assists in operating the armature controlling the contacts of the control device. This auxiliary magnet may be attached to the apparatus in a simple manner without disturbing its construction.

The invention is by way of example more particularly described with reference to the accompanying drawing in which—

Figure 1 is a vertical view, partly in section, of a combined switch and regulator together with a circuit diagram of an electrical installation as used in power driven vehicles, and Figure 2 is a vertical view of a modified construction also embodying the principles of the invention.

In both figures the same reference characters are employed to indicate similar parts.

Referring to Fig. 1, the armature and field winding of a lighting dynamo or generator are indicated at 1 and 2, respectively, a resistance 3 being connected in series with the field winding 2 and adapted to be intermittently shunted out in the course of voltage regulation. The regulation of voltage is effected by means of a voltage coil 4 of a combined regulator switch unit which is disposed on an electromagnetic core 5, carrying a current coil 6 and disposed on the yoke of a U-shaped magnet frame 7. The voltage coil 4 actuates two right angle shaped armatures 8 and 9, which are suspended for limited angular movement by springs 8a, 9a, disposed on the ends of the limbs 7a, 7b of the magnet frame 7. The vertical limbs of said armatures 8 and 9 are approximately parallel to the main pole core 5. The armature 8 is adapted to actuate the contacts 10 and 11 of the automatic switch, the vertical armature limb 8b having attached thereto a spring 8c which carries the contact 11, and the contacts 10, 11, being open except when the core 5 is sufficiently energized as hereinafter explained. The horizontal armature limb 8d extends over the end of the core 5 in cooperating relation therewith. The armature 9 is adapted to actuate the contacts 12 and 13 of the voltage regulator, these contacts remaining closed except when core 5 is sufficiently energized by voltage coil 4.

The armature 8 regulates the voltage of the dynamo 1, 2, in known manner, by periodically opening and closing the contacts 12, 13. The armature 8 controls the output from the dynamo 5 by connecting or disconnecting an external current consuming circuit in known manner.

Through a slot provided in limb 7a of the magnet frame 7 on which the armature 8 is mounted, passes the core 14 of an auxiliary magnet. The core 14, which is thus disposed transversely to the main core, specifically at right angles thereto, carries a current coil 15 and is supported by a right angle shaped magnet frame 16 fixed to the top of said limb 7a.

Through a slot provided in limb 7a of the magnet frame 7 on which the armature 8 is mounted, passes the core 14 of an auxiliary magnet. The core 14, which is thus disposed transversely to the main core, specifically at right angles thereto, carries a current coil 15 and is supported by a right angle shaped magnet frame 16 fixed to the top of said limb 7a.

As soon as the dynamo produces a sufficiently high voltage, the armature 8 is attracted as a result of the excitation of the voltage coil 4 and closes the contacts 10, 11 of the switch, whereupon electric current from the dynamo flows through the two current coils 6 and 15 to a battery 17 or to current consuming elements 18. As to the sense of magnetisation, the action of the current coils 6 and 15 is the same as of the voltage coil 4. The magnetisation of the core 14 produced by the current coil 15 attracts armature limb 8b which extends over the end of the core in cooperating relation therewith. There are, then, two magnetic fluxes present. One passes through the magnet core 5, through the half of the magnet frame 7 assigned to the switch and through the armature limb 8d. The other passes through the auxiliary magnet core 14, through the magnet frame 16 and through the armature limb 8b which extends over the end of the core 14. Consequently this limb comes to rest on the end of the core 14 so that in this position, the air gap disappears and the armature 8 adheres to the end of the auxiliary core. The armature 8 thus becomes insensitive to vibration produced during driving of the vehicle on which the device is mounted so that there is no danger of such vibration opening the switch contacts 10, 11.

The core 14 of the auxiliary magnet acts as an additional pole surface beyond the main core 5 to attract the armature 8. Thus the regulator and the switch though constructed in one unit become more independent from one another. Under normal operating conditions the regulator armature 8 swings freely under the influence of the voltage coil 4 and the current coil 6 to effect the desired regulation of the dynamo output. At the same time the switch armature 8 is strongly held by the additional pole surface of the core 14, thereby holding contacts 10, 11 firmly closed.

If the voltage generated by the dynamo falls below that of the battery so that a reverse current flows through the current coil 15 of the auxiliary magnet 14, 15, then the armature 8 is released from the core 14 and is moved by spring 8a to open the switch contacts 10, 11. This arrangement has the advantage that the switch responds even to a small reverse current.

The auxiliary magnet removes the possibility of any chance short circuit in the current-consuming circuit opening and closing the switch contacts in rapid sequence, in the event of a strong current, and consequently damaging them. The customary use of a bimetallic construction for the switch contact springs is therefore not necessary in this case.

As will be seen from the drawing, the application of the auxiliary magnets 14, 15 to the top of the limb of the magnet frame 7 results in a very compact construction. The approved construction of regulator switches with a U-shaped magnet frame is likewise retained.

Referring to Fig. 2, the arrangement differs from that of Fig. 1 in that the armatures 8 and 9 are suspended by springs 19 and 20 disposed on supports 21 and 22 which are fastened to the limbs 23 and 24 of the magnet frame 7 and that the core 14 carrying the current coil 15 is disposed on the inner side of the magnet limb 23.

The construction of Fig. 2 is more simple than that of Fig. 1, for there no separate angle shaped core supports are needed because the core 14 is disposed directly on the limb 23 of the magnet frame 7.

The limbs 23, 24 do not as hitherto known extend to the horizontal supports of the angle shaped armatures, but are shortened. This arrangement has an advantageous effect on the magnetic flux. The magnetic leakage is reduced.

The auxiliary magnet makes it possible to provide the main electromagnet in a simple manner with a winding which is not wound on the main core. Hitherto a winding of this sort was pushed on to the limb of the magnet frame, which was a complicated process from the point of view of fastening the armature and arranging the contacts.

As the auxiliary core 14 has a small diameter as compared with the main core 5 the current coil 15 which is wound on to it requires only a short winding.

5 As shown in the drawing by way of example the main core 5 carries a voltage coil 4 and a current coil 6 for regulation purposes.

The auxiliary magnet 14, 15 for the automatic switch may, however, on the omission of the current coil 6 be applied to regulator switches which have only a voltage coil for regulation.

I declare that what I claim is:

1. An electromagnetic device for controlling the output of a generator to an external current-consuming circuit, comprising the combination, with a U-shaped magnet frame, of a main pole core disposed intermediate and substantially parallel to the upright limbs of the frame, an auxiliary pole core carried by one of said limbs and disposed transversely with respect to the main core, an angularly movable armature having angularly related limbs which extend over the ends of the respective pole cores, windings so arranged on said cores that, when energized, both cores tend to move said armature in the same angular direction, the winding on said auxiliary core being in series with the current-consuming circuit, and switch contacts operable by said armature to connect the generator to said circuit, energization of the main core winding serving to move said armature sufficiently to close said contacts, whereupon energization of the auxiliary core by flow of current to the current-consuming circuit causes the cooperating limb of the armature to be held against the end of said auxiliary core.

2. An electromagnetic control device as defined in claim 1, wherein the main core also carries a current winding in series with that on said auxiliary core and arranged to exert its magnetic force in the same sense as said voltage coil.
